UNITED STATES PATENT OFFICE.

CHARLES A. SHEDD, OF WORCESTER, MASSACHUSETTS, ASSIGNOR TO WALDEN-WORCESTER, INC., OF WORCESTER, MASSACHUSETTS, A CORPORATION OF MASSACHUSETTS.

DESIGN FOR AN AUTOMOBILE WRENCH.

60,270.

Specification for Design. Patented Jan. 17, 1922.

Application filed June 9, 1920. Serial No. 387,760. Term of patent 7 years.

To all whom it may concern:

Be it known that I, CHARLES A. SHEDD, a citizen of the United States, residing in Worcester, county of Worcester, and State of Massachusetts, have invented a new, original and ornamental Design for an Automobile Wrench, of which the following is a specification, reference being had to the accompanying drawing, forming a part thereof.

Figure 1 is a top plan view of a wrench embodying my invention;
Figure 2 is an elevation thereof;
Figure 3 is a bottom plan view thereof.
What I claim is—
The ornamental design for an automobile wrench, as shown.

CHARLES A. SHEDD.
